UNITED STATES PATENT AND TRADEMARK OFFICE
Certificate

Patent No. D.616,333 S

Patented: May 25, 2010

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Ian Cartabiano, Newport Beach, CA (US); Hiroyuki Hatake, Toyota (JP); Shunsaku Kodama, Toyota (JP); and Masayuki Yamada, Toyota (JP).

Signed and Sealed this Twenty-second Day of March 2011.
